United States Patent Office

Des. 205,805
Patented Sept. 20, 1966

205,805

SLIDE PROJECTOR

Robert M. Simonelli, Des Plaines, and Thomas M. Steinbach, Park Ridge, Ill., assignors to Sawyer's Inc., Portland, Oreg., a corporation of Oregon

Filed Sept. 10, 1965, Ser. No. 86,948

Term of patent 14 years

(Cl. D61—1)

FIG-4-

FIG-5-

FIG. 1 is a perspective view showing the front, side and top of a slide projector embodying our new design; FIG. 2 is a front elevational view thereof; FIG. 3 is a rear elevational view thereof; FIG. 4 is a top plan view thereof; FIG. 5 is a side elevational view thereof; FIG. 6 is a side elevational view thereof, the side shown being opposite of the side shown in FIG. 5; and FIG. 7 is a bottom plan view thereof.
We claim:
The ornamental design for a slide projector, substantially as shown.
